(57) **CLAIM**

The ornamental design for a shed loft, as shown and described.

DESCRIPTION

FIG. 1 is a top front right perspective view of a shed loft, showing our new design;

FIG. 2 is a top rear right view thereof;

FIG. 3 is a top view thereof;

FIG. 4 is a bottom view thereof;

FIG. 5 is a right side view thereof;

FIG. 6 is a left side view thereof;

FIG. 7 is a front view thereof;

FIG. 8 is a rear view thereof;

FIG. 9 is a bottom rear right view thereof; and,

FIG. 10 is a bottom front right view thereof.

The portions of the shed loft illustrated in broken lines form no part of the claimed design.
